ELECTRIC CAN OPENER WITH SWITCH IN BASE

Lealand H. Johnson and Wesley W. Tull, Seminole, Okla.

Application April 17, 1956, Serial No. 578,610

11 Claims. (Cl. 30—4)

This invention comprises a novel and useful can opener and more specifically pertains to an automatic electrically operated can opener having a greatly improved construction and mode of operation.

The primary object of this invention is to provide a can opener which will greatly facilitate and speed up the opening of cans of liquids such as beer and the like.

A further object of the invention is to provide a can opener whose operation shall be entirely automatic and will be initiated by the placing of a can in proper position below the operating elements of the can opener.

A further object of the invention is to provide an improved can opener which will eliminate the unsanitary and unhygienic conditions attending the opening of cans by manual can openers which are frequently exposed to dirt and other unsanitary conditions during their periods of non-use.

A still further object of the invention is to provide a can opener in accordance with the preceding objects which will largely eliminate the possibility of injury to the user by the jagged surfaces of cans or the points or blades of other can openers.

Yet another object of the invention is to provide an automatic can opener whose base will facilitate the positioning of cans for the automatic opening of the same and will also collect any spilling or overflow of the contents of the cans during their opening.

Yet another important purpose of the invention is to provide a can opener in conformity with the foregoing objects which may be very easily disassembled for compact storage, or for servicing or replacement of any of its parts.

A still further object of the invention is to provide a can opener which shall be automatic in its operation and will be actuated by electrical means, and wherein a switch for controlling the automatic operation will be mounted in the base of the opener and at a position remote from the opener blade of the device, to thereby minimize the possibility of injury to the hands of the operator by accidental operation of the switch.

A further and very important purpose of the invention is to provide an automatic can opener in accordance with the foregoing objects wherein the operating head of the device may be readily vertically adjustable upon supporting standards to adapt the same to accommodate different sizes of cans.

A still further important object of the invention is to provide an automatically operated can opener wherein the solenoid for actuating the same may be securely positioned upon and supported by a member which is vertically adjustable upon a plurality of standards, and wherein in the enclosing housing of the solenoid and blade together with the combined sanitary plate and stop means

2

for the blade may be carried by and directly vertically adjusted together with the plate supporting the solenoid.

Yet another and more specific object of the invention is to provide an automatic electrically operated can opener wherein the maximum power of the solenoid plunger shaft shall be utilized for operating the can opening blade by directly mounting the latter thereon.

A further important object of the invention is to provide an automatically electrically operated can opener as set forth in the foregoing objects wherein the wiring may be water-proofed by concealment in one of the supporting standards of the device.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in vertical central section through a preferred embodiment of a can opener incorporating therein the principles of this invention, the positioning of the can therein for opening and the removal of the can therefrom after opening being shown in full lines, while the position of the can for the automatic opening operation being shown in dotted lines therein;

Figure 2 is a horizontal sectional view taken substantially upon the plane indicated by the section line 2—2 of Figure 1 and showing in particular the locking means whereby the can opener head assembly including the solenoid carrier plate for supporting the same is releasably locked in vertically adjusted position upon the supporting standards of the device;

Figure 3 is a horizontal sectional detail view taken substantially upon the plane indicated by the section line 3—3 of Figure 1;

Figure 4 is a horizontal sectional view taken substantially upon the plane indicated by the section line 4—4 of Figure 1 and also disclosing the manner in which the solenoid plunger is slidably guided in the solenoid carrier plate and stop plate;

Figure 5 is a bottom plan view of the base of the can opener;

Figure 6 is a front elevational view showing a portion of the can opener head assembly, and the supporting base therefor;

Figure 7 is a detail view partly in vertical section through the lower end of the solenoid plunger shaft and the knife blade opener carried thereby; and

Figure 8 is a fragmentary perspective view showing a can after the same has been opened by this can opener.

As shown in the accompanying drawings, a suitable embodiment of apparatus for carrying out the principle of this invention consists of a supporting base 10 of a preferred construction to be subsequently set forth, and upon which is mounted a head assembly 12 carrying the operating parts of the can opener, there being a plurality of support standards 14 by which the head assembly is supported above the base together with a tubular standard 16.

As will be seen especially by reference to Figures 1, 3—6, the base 10 includes a body of suitable material having a substantially flat bottom surface 18 to which are secured suitable suction cups 20 for supporting the base. The base is provided with a substantially U-shaped depression, the same consisting of elevated side walls 22 together with a back wall 24, and a forwardly sloping

bottom wall 26 which inclines downwardly from the back wall towards the open front end of the base.

As will be best seen from Figures 1 and 5, the under-surface of the base and its back wall are upwardly recessed as at 30 to conveniently conceal and house an electric conductor 32 by means of which electric current may be supplied to the automatic can opener. It will be observed that the tube 16 has its lower end screw threadedly engaged as at 34 in a bore 36 opening upwardly from the recess 30, whereby to receive electric conductors 38 which form a part of the electrical circuit of the device. A switch 40 is received in a further pocket or recess 42 opening upwardly from the recess 30, being removably retained therein as by a screw or bolt 44. This switch has a forwardly projecting actuating finger or button 46 which extends through the back wall 24 closely adjacent to floor 26 of the base and below the operating head 12 whereby the same may be actuated by the lower portion of the wall of a can 50 when the latter is placed upon the base as will be apparent from Figure 1.

Although this switch may be of any suitable construction, it is preferred to form the same as a single pole, normally opened at each end of its travel and closed at the mid-portion thereof whereby the switch will be normally opened, then closed when the lower end of a can moves the plunger to an intermediate position and is again opened when the can be pressed backwardly against the back wall, as will be apparent from the dotted line showing of Figure 1. However, when the can is moved away from the back wall, as shown in full lines in Figure 1, the switch will return to its inoperative forward position.

It is especially important for the purposes of this invention that the switch shall be in this location inasmuch as any possibility of the hand of the operator being injured by the descending knife blade of the opener upon accidental manipulation of the switch button 46, is thus avoided.

Referring next primarily to Figure 1 it will be seen that the head 12 consists of a housing or casing 52 which is preferably cylindrical in shape and constructed of sheet metal, the same being provided with a closed upper head portion 53. At a convenient position within the casing 52, and disposed above the open lower end of the same is a transversely extending plate 54 which constitutes a carrier or hanger plate for the operating elements of the can opener. This plate is provided with suitable apertures slidably embracing the two standards 14 and the tubular posts 16 as will be apparent from Figure 4, and also is provided with a non-circular central opening 56 for slidably and guidably receiving the solenoid plunger shaft 58 in a manner to be subsequently set forth. Referring particularly to Figure 7 it will be seen that the lower end of this shaft is round and is externally screw threaded as at 60 for detachably receiving an opening or cutter blade 62. The latter has an opening point 64 with rearwardly divergent side edges 66 and a forwardly and upwardly convergent single point or edge 68.

This cutter blade is so shaped that it will cut a substantially triangular opening as at 70, see Figure 6, in the top of the can, this opening having an elongated apex to constitute a vent for the can. The single blade secured to the solenoid shaft thus serves both to vent and open a can for dispensing its contents.

The cutter blade has a flat upper surface as at 72 which is adapted to abut against the underside of the plate 54 and thus limit upward travel of the blade.

Carried by the plate 54 is a solenoid casing 74, which rests upon the plate 54 and is clamped thereto as by the fastening bolts 76 and a clamping ring 78. The ring in turn is secured as by screws 80 to the upper or top surface of the solenoid housing 74, as will be apparent from Figures 1 and 2.

As will be observed from Figure 1, the upper ends of the conductors 38 extend from the open upper end of the tube 16 whose upper end is slidably extended through the

carrier plate 54, and from thence are attached to the winding of the solenoid, in a manner well understood in the art and therefore deemed to be unnecessary for a detailed showing in the drawing.

5 The armature or core of the solenoid 82 projects upwardly above the top surface of the solenoid housing 74, and is provided with an enlarged head 84, while a compression spring 86 surrounds the solenoid and abuts against the housing and the head to yieldingly urge the 10 solenoid to its upward or raised position, this upward position being limited by the above mentioned engagement of the top surface 72 of the knife blade with the underside of the carrier plates 54. When the solenoid is energized, the plunger and the plunger shaft 58 will be 15 driven downwardly, thus moving the blade from its full line to its dotted line position as shown in Figure 1 and thus venting and opening the top of a can.

A simple and highly effective locking means is provided 20 whereby the entire head assembly may be vertically adjusted upon the standards 14 for adapting the device to receive and operate upon different heights of cans. For this purpose the standards 14 are provided with a plurality of vertically spaced latching recesses or slots 88. From Figure 2 it will be seen that the slots 88 in the two standards are disposed on opposite sides of the same, and a latching arcuately shaped blade or lever 90 is pivotally secured to the ring 78 and its top of the solenoid 74 as by a pivot screw 92, this latch lever having at one extremity 94 a locking screw 96 extended through an arcuately extending slot 98 of the housing.

A leaf spring 100 is suitably mounted and operatively 25 associated with the latch lever 90 to yieldingly urge the same into latching engagement with a selected pair of notches 88 in the two standards. In order to adjust the 30 device it is merely necessary to release the locking screw 96, whereupon the lever may be rotated in a clockwise direction as viewed in Figure 2 to release the end portions of the lever 90 from the notches 88, whereupon the entire head assembly may be vertically adjusted upon the standards 14 and the spring 100 will again urge the latch lever 90 into its locking position, whereupon the screw 96 may be tightened to secure the same in such 35 adjusted position.

Referring now to Figures 1 and 3 it will be seen that the lower open end of the housing 52 of the head assembly is provided with a removable combined closure plate, sanitary shield and stop means, designated by the 40 numeral 102. This plate is provided with a central aperture or opening 104 appropriately shaped to permit passage of the cutting edges 68, 64 and 66 of the knife blade therethrough, under the impulse of the solenoid winding coil, when the switch 40 is actuated, and to permit retraction of the blade, as from the dotted lines to the full lines showing of Figure 1 when the solenoid is de-energized, under the thrust of the spring 86. This plate is provided with a curved depending flange or shield 106 which is adapted to receive the upper edge of the can and prevents splashing of its contents, whereby any liquid spilled from the can will be collected upon the bottom wall 26 and drained therefrom to the front of the device.

45 The plate 102 is provided with suitable apertures for slidably receiving the standards 14 and the tube 16 therethrough, and the plate is releasably retained as by a thumb screw 108. When it is desired to clean, service or replace the blade 62, it is merely necessary to remove the plate 102 by releasing the thumb screw 108 and dropping the plate downwardly along the standards and column, whereby access may be had to the knife blade.

50 It will thus be seen that the plate 102 with its depending guard 106 serves to guide the can 50 into position for opening by the device, and constitutes a stop means limiting movement of the upper end of the can, whereby the upper end may be placed against this guide means and the lower end pushed into position against the switch button 46 thereby activating the opening element of the

device. As soon as the can top has been punctured, and the can has pushed the switch button 46 all the way in, the switch will be again opened and the operator may pull the lower end of the can into the full line position of Figure 1, freeing the can for removal from the device.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A can opener comprising a base including a drain tray, a head assembly, a pair of standards for supporting a head assembly above said base, said head assembly including a hood enclosing the upper portion of said standards, a cutter blade for venting and punching the top of a can when disposed therebeneath, spring means in said hood yieldingly raising said cutter blade, means of imparting a downward punching stroke to said blade, means mounting said cutter blade in said hood for vertical reciprocation, means in said hood for vertically adjusting the head assembly upon said standards, said last means including a plurality of vertically spaced latch notches on said standards, a latch lever within said hood and pivotally supported thereon for engaging said notches.

2. A can opener comprising a base including a drain tray, a head assembly, a pair of standards for supporting a head assembly above said base, said head assembly including a hood enclosing the upper portion of said standards, a cutter blade for venting and punching the top of a can when disposed therebeneath, spring means in said hood yieldingly raising said cutter blade, means of imparting a downward punching stroke to said blade, means mounting said cutter blade in said hood for vertical reciprocation, means in said hood for vertically adjusting the head assembly upon said standards, said last means including a plurality of vertically spaced latch notches on said standards, a latch lever within said hood and pivotally supported thereon for engaging said notches, said latch notches being disposed on opposite sides of said standards, said latch lever extending between said standards.

3. A can opener comprising a base including a drain tray, a head assembly, a pair of standards for supporting a head assembly above said base, said head assembly including a hood enclosing the upper portion of said standards, a cutter blade for venting and punching the top of a can when disposed therebeneath, spring means in said hood yieldingly raising said cutter blade, means of imparting a downward punching stroke to said blade, means mounting said cutter blade in said hood for vertical reciprocation, means in said hood for vertically adjusting the head assembly upon said standards, said last means including a plurality of vertically spaced latch notches on said standards, a latch lever within said hood and pivotally supported thereon for engaging said notches, said hood having a slot, a locking device for securing the latch lever in said notches extending through said slot.

4. A can opener comprising a base including a drain tray, a head assembly, a pair of standards for supporting a head assembly above said base, said head assembly including a hood enclosing the upper portion of said standards, a cutter blade for venting and punching the top of a can when disposed therebeneath, spring means in said hood yieldingly raising said cutter blade, means of imparting a downward punching stroke to said blade, means mounting said cutter blade in said hood for vertical reciprocation, means in said hood for vertically adjusting the head assembly upon said standards, said hood having a carrier plate extending across the same and fixedly secured thereto, said plate having apertures slidably receiving said standards, said cutter blade, spring

means, stroke imparting means and said head adjusting means being carried by said plate.

5. A can opener comprising a base including a drain tray, a head assembly, a pair of standards for supporting a head assembly above said base, said head assembly including a hood enclosing the upper portion of said standards, a cutter blade for venting and punching the top of a can when disposed therebeneath, spring means in said hood yieldingly raising said cutter blade, means of imparting a downward punching stroke to said blade, means mounting said cutter blade in said hood for vertical reciprocation, means in said hood for vertically adjusting the head assembly upon said standards, said hood having a carrier plate extending across the same and fixedly secured thereto, said plate having apertures slidably receiving said standards, said cutter blade, spring means, stroke imparting means and said head adjusting means being carried by said plate, a closure plate detachably mounted within the hood beneath said carrier plate, a splash shield depending from the closure plate for partially encircling the upper portion of a can to be opened.

20 6. A can opener comprising a base including a drain tray, a head assembly, a pair of standards for supporting a head assembly above said base, said head assembly including a hood enclosing the upper portion of said standards, a cutter blade for venting and punching the top of a can when disposed therebeneath, spring means in said hood yieldingly raising said cutter blade, means of 25 imparting a downward punching stroke to said blade, means mounting said cutter blade in said hood for vertical reciprocation, means in said hood for vertically adjusting the head assembly upon said standards, said hood having a carrier plate extending across the same and fixedly secured thereto, said plate having apertures 30 slidably receiving said standards, said cutter blade, spring means, stroke imparting means and said head adjusting means being carried by said plate, a closure plate detachably mounted within the hood beneath said carrier plate, a splash shield depending from the closure plate for partially encircling the upper portion of a can to be opened, said closure plate having an opening for passage of said cutter blade therethrough.

7. An electric can opener comprising a base, means for 45 supporting a head assembly above said base for puncturing a can positioned on said base and therebeneath, a pair of standards and a tube rising from said base, said head assembly including a carrier plate apertured for sliding and guided vertical movement on said standards and tube, a hood mounted on and enclosing said carrier plate and 50 said standards and tube, a solenoid having an armature mounted on said carrier plate, a cutter blade directly carried by said solenoid and depending therebeneath, electric conductors for said solenoid extending through 55 said tube, means for securing said head assembly in vertically adjusted position on said standards.

8. The combination of claim 7 including a switch controlling said solenoid and mounted on said base, an actuator button for said switch positioned for engagement by 60 the lower portion of a can when the latter is placed upon the base directly below said head assembly.

9. The combination of claim 7 including a combined safety shield and splash guard comprising a closure plate releasably secured in the hood below said cutter blade in 65 its raised position, said closure plate having an aperture for passage of the cutter blade therethrough during its operation, said closure plate being apertured for sliding passing upon said standards and tube.

10. The combination of claim 7 including a combined 70 safety shield and splash guard comprising a closure plate releasably secured in the hood below said cutter blade in its raised position, said closure plate having an aperture for passage of the cutter blade therethrough during its operation, said closure plate being apertured for sliding 75 passing upon said standards and tube, an arcuate splash

apron depending from said closure plate for encircling the upper portion of a can to be opened.

11. A can opener comprising a base, a pair of standards rising from said base, a head assembly carried by said standards, said head assembly including a vertically movable cutter blade for venting and punching the top of a can when disposed therebeneath, means for raising said cutter blade, means for imparting a downward punching stroke to said blade, means for vertically adjusting said head assembly upon said standards including a plurality of vertically spaced latch notches on said standards, a latch

lever pivotally secured to said head assembly for engaging said notches.
